UNITED STATES PATENT OFFICE

2,059,840

REFRIGERATING MACHINE

Leonard W. Atchison, Schenectady, N. Y., assignor to General Electric Company, a corporation of New York

Application August 21, 1934, Serial No. 740,787

9 Claims. (Cl. 62—116)

My invention relates to refrigerating machines.

An object of my invention is to provide a refrigerating machine having an evaporator which shall require minimum space within the compartment to be cooled and which shall be simple and of rugged construction.

Another object of my invention is to provide an evaporator for refrigerating machines which shall form a part of the lining of the compartment to be cooled.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawings in which Fig. 1 is a side elevation partly in section of a refrigerating machine having an evaporator embodying my invention; Fig. 2 is a detail perspective view of the evaporator shown in Fig. 1, with the freezing shelf detached therefrom and Fig. 3 is a vertical sectional view on the line 3—3 of Fig. 2 of the evaporator with the freezing shelf attached thereto.

Referring now to the drawings, in Fig. 1 I have shown a household refrigerator cabinet 10 having an outer wall 11 and divided by a wall 12 near the middle of the cabinet into two compartments. The upper compartment is provided with an inner liner 13 forming a cooling chamber 14, and heat insulation 15 is arranged between the inner liner 13 and the walls 11 and 12. The walls 11, 12 and 13 are preferably made of sheet metal. The cooling chamber is provided with a heat insulated door 16 at the top thereof. In order to cool the chamber 14 I provide an evaporator 17 secured to the outside of the liner 13 and between the liner 13 and the outer wall 11, and provide a shelf 18 within the compartment. The shelf 18 supports freezing trays or the like and is constructed of a material of high thermal conductivity, such as aluminum. In order to supply refrigerant to the evaporator 17, a closed casing 19 having a motor and a compressor arranged therein is mounted in the lower compartment. Refrigerant is compressed by the compressor within the casing 19 and discharged from the compressor into a conduit 20, through which it flows to a condenser comprising conduits 21 and 22 secured in heat exchange relation to the inner surface of the outer wall 11 of the cabinet and connected by a conduit 23. This construction, wherein the

condenser conduit is secured in heat exchange relation to the outer wall of a refrigerator cabinet, is described and claimed in a copending application of Christian Steenstrup, Serial No. 554,623, filed August 3, 1931, and assigned to the General Electric Company, assignee of my present invention. I do not, therefore, claim herein anything described or claimed in the said Steenstrup application, which is to be regarded as prior art with respect to this present application, my invention relating to an evaporator construction, and its arrangement in a cabinet structure. The refrigerant is condensed and liquefied within the condenser conduits 21 and 22 and flows through a connection 24 to a receiver or float valve chamber 25. Refrigerant is discharged from the float chamber under the control of a float therein and flows through a connection 26 to the evaporator 17 where it is vaporized upon the absorption of heat from the chamber 14 and is withdrawn through a suction conduit 27 and returns to the casing 19, the interior of which is on the low pressure side of the compressor therein.

Referring now to Fig. 2 the evaporator 17 comprises a sheet of metal 28 welded or otherwise suitably secured face to face with the inner metal liner 13 of the refrigerator cabinet. The sheet 28 is provided with indentations forming an upper header 29 and a lower manifold 30 connected by a plurality of upright refrigerant circulating passages 31. The sheet 28 is welded, or otherwise secured in some suitable manner, to the liner 13 around the edges of the sheet and along the surface between the indentations extending the entire length of indentations 31, where the sheet 35 and the liner are in face engagement. The liner of the compartment to be cooled thus forms one wall of the evaporator, and the evaporator takes up no space within the compartment. In order that water, desserts or the like may be frozen, I provide the shelf 18, which is constructed of aluminum or some other suitable material of high thermal conductivity, secured in good heat exchange relation to the evaporator adjacent the header by bolts 32 as shown in Fig. 3 which pass 45 through holes 33 and 33a in the evaporator and shelf 18 respectively. Liquid refrigerant is supplied to the evaporator 17 through supply conduit 26, a short tube 34 which is connected to one end of the manifold 30, and a conduit 35 extending within the manifold 30 and substantially the entire length thereof. The conduit 35 is provided with orifices 36, one opposite every other one of the upright refrigerant passages 31. The level of liquid refrigerant in the header 29 is pref- 55

erably always maintained above the upper ends of the upright passages 31. Liquid flowing into the evaporator through the orifices 36 will set up a circulation of refrigerant from the header 5 through the passages 31 and manifold 30, as indicated by the arrows shown in the cut-away portion in Fig. 2, the refrigerant being circulated upwardly through the passages 31 which are above the orifices 35 and downwardly through the other alternate passages. A rapid and efficient circulation of liquid refrigerant within the evaporator is thus produced. Since the shelf 18 is in good heat exchange relation with the evaporator 17 water, desserts, or the like placed 10 in freezing trays supported on the shelf may readily be frozen. The shelf 18 is of simple construction, is easily cleaned and presents a minimum obstruction of space within the compartment to be cooled. The evaporator 17 is embedded 15 in the insulation 15 within the walls of the compartment 14 and any substantial absorption of heat from the air outside the compartment is thereby prevented.

It is apparent from the foregoing that I have provided a refrigerating machine having an evaporator of simple and rugged construction which requires a minimum amount of material, occupies substantially no space within the compartment to be cooled, and provides adequate cooling and 20 ice freezing capacity.

While I have described my invention in connection with a household refrigerator, I do not desire my invention to be limited to the construction shown and described, and I intend in 25 the accompanying claims to cover all modifications within the spirit and scope of my invention.

What I claim as new and desire to secure by Letters Patent in the United States is:

1. A refrigerating machine including a cabinet 40 having thermally insulated walls providing a compartment to be cooled, a liner for said compartment, and means including an evaporator comprising a sheet of metal secured face to face with said liner for cooling said compartment, said sheet having indentations therein providing a header and refrigerant passages between said sheet and said liner.

2. A refrigerating machine including a cabinet 50 having a compartment to be cooled, a liner for said compartment, means including an evaporator comprising a sheet of metal secured face to face with said liner for cooling said compartment, said sheet having indentations therein providing a header and refrigerant passages between said sheet and said liner, and means injecting liquid refrigerant into said refrigerant passages for producing a circulation of refrigerant in said evaporator.

3. A refrigerating machine including a cabinet 60 having a compartment to be cooled, a liner for said compartment, means including an evaporator comprising a sheet of metal secured face to face with said liner for cooling said compartment, said sheet having indentations therein providing a header and a manifold and a plurality of upright refrigerant passages connecting said header and said manifold, and means including a conduit entering said manifold and injecting liquid refrigerant into alternate ones of said upright 65 passages in said evaporator for producing a circulation of refrigerant within said evaporator.

4. A refrigerating machine including a cabinet having thermally insulated walls providing a compartment to be cooled, a liner for said compartment, and means including an evaporator arranged within said walls and comprising a sheet of metal secured face to face with said liner for cooling said compartment, said sheet having indentations providing a header and a manifold and a plurality of upright refrigerant passages connecting said header and said manifold. 10

5. A refrigerating machine including a cabinet having a compartment to be cooled, a liner for said compartment, means including an evaporator comprising a sheet of metal secured face to face with said liner for cooling said compartment, said sheet having indentations providing a header and a manifold, and means including a shelf 15 constructed of a material of high thermal conductivity secured to said liner within said compartment adjacent said header for supporting freezing trays and the like within said compartment. 20

6. A refrigerating machine including a cabinet having a compartment to be cooled, a liner for said compartment, heat insulating material surrounding said compartment, and means including an evaporator comprising a single sheet 30 of metal providing a header and arranged in heat exchange relation with said liner for cooling said compartment, said header being embedded in said heat insulating material.

7. A refrigerating machine including a cabinet 35 having a compartment to be cooled, a liner for said compartment, heat insulating material surrounding said compartment, means including an evaporator having a header and arranged in heat exchange relation with said liner for cooling said compartment, said header being embedded in said heat insulating material, and means including a shelf constructed of a material of high thermal conductivity secured to said liner within said compartment adjacent said header for supporting freezing trays and the like 40 within said compartment. 45

8. A refrigerating machine including a cabinet having a compartment to be cooled, a liner for said compartment, means including an evaporator comprising a sheet of metal secured face to face with said liner for cooling said compartment, said sheet and said liner having a refrigerant passage formed therebetween, and means including a shelf constructed of a material of high 50 thermal conductivity secured to said liner within said compartment adjacent said evaporator for supporting freezing trays and the like within 55 said compartment.

9. A refrigerating machine including a cabinet 60 having thermally insulated walls providing a compartment to be cooled, a liner for said compartment, and means including an evaporator comprising a sheet of metal secured face to face with said liner for cooling said compartment, 65 said evaporator comprising a header and refrigerant conduits arranged between said sheet and said liner.

DISCLAIMER

2,059,840.—*Leonard W. Atchison*, Schenectady, N. Y. REFRIGERATING MACHINE.
Patent dated November 3, 1936. Disclaimer filed July 7, 1939, by the
assignee, *General Electric Company*.

Hereby enters this disclaimer to claims 1 and 9 of said patent.
